UNITED STATES PATENT OFFICE.

EDWIN L. HARMAN, OF NORTH MANCHESTER, INDIANA.

AUTOMATIC SIGNALING AND DETECTING DEVICE FOR VENDING-MACHINES OR THE LIKE.

No. 830,064.

Specification of Letters Patent.

Patented Sept. 4, 1906.

Application filed July 29, 1904. Serial No. 218,663.

To all whom it may concern:

Be it known that I, EDWIN L. HARMAN, a citizen of the United States, and a resident of North Manchester, in the county of Wabash and State of Indiana, have invented certain new and useful Improvements in Automatic Signaling and Detecting Devices for Vend-
5 ing-Machines or the Like; and I do hereby declare that the following is a full, clear, and
10 exact description of the same, reference being had to the accompanying drawings, and to the letters of reference marked thereon, which form a part of this specification.

This invention relates to automatic signaling and detecting devices for coin-operated machines, and is herein shown as more particularly embodied in a pay-telephone, though, obviously, it may be used in connection with any desired coin-operated vending-
20 machine.

Heretofore in many classes of coin-operated vending-machines it has been possible to operate them with coins of light weight or of different denomination than that designed
25 to operate the machine, and it has also been possible to operate them with slugs or disks of other metal, thereby causing a loss of profits for said machines.

The object of this invention is to provide a
30 device whereby slugs or disks of inferior metal or coins of lighter weight or different denomination than those designed to operate the machine are detected and either returned or deposited within the machine without
35 coming in contact with the operating mechanism.

It is also an object of the invention to provide an audible signal operated by the moving coin and if used in telephone-circuit acting
40 simultaneously with the usual or any visible signal, should the same be required.

The invention consists in the matters hereinafter described, and more fully pointed out and defined in the appended claims.

45 In the drawings, Figure 1 is a front elevation, partly broken, of a vending or slot machine of any kind provided with a device embodying my invention. Fig. 2 is an enlarged side elevation of the device, showing the position of the parts after the dropping of the coin. Fig. 3 is a similar view showing the opposite side of the machine. Fig. 4 is a view similar to Fig. 3, showing the adjustment just prior to the drop of the coin. Fig. 5 is a top plan view. Fig. 6 is a central longitudinal section. Fig. 7 is a rear elevation.

Fig. 8 illustrates a detail of a pivoted door closing the opening into the coin-chute.

As shown in said drawings, the front wall A of a telephone-box or other prepayment device with which my invention is adapted to be used is provided on its inner side with a standard or frame member A', herein shown as metallic, which is rigidly bolted or otherwise secured thereon in close relation thereto. 60 A side frame member A² is rigidly secured on said frame member A' adjacent one side thereof and extends therefrom at approximately a right angle and upwardly, as shown, to a point below the top of the frame member A' and at its top affords a straight edge a at a right angle with the plane of the frame-plate A'. Rigidly secured on said frame members at a slight distance below the upper edge a of the frame member A² is a horizontal table A³, which extends forwardly through a suitable aperture in the frame-plate A' and the wall A and is provided on its outer end with lateral upwardly-directed inturned lugs a' a' and at its inner end with an upwardly- 70 directed transverse flange a², as shown, flush with the edge a of the standard A². Slidably engaged on said table with the upper surface thereof in close relation to the top of the aperture in the wall A and the standard A' is a 75 coin-feed slide B, provided on its outer end with an upturned handle b for manually operating the same and having at each side an upturned flange b', which engages between and beneath the inturned lugs a'. Said lugs 80 and flanges, together with parts of the frame-plate A' and the top a of the frame member A², form guides for the movement of said feed-slide on the table and prevent its displacement therefrom. Rigidly se- 85 cured one on each side the center at the inner end of said feed-slide B and projecting laterally beyond the sides of the table are the stud-shafts or trunnions b³ b⁴. When said feed-slide is in its outermost position, as 90 shown in Figs. 2, 3, 5, and 6, the stud-shafts or parts thereon engage the inner face of the frame member A' and limit the outward movement of the slide. In the inner end of said slide is an aperture b⁵ of sufficient di- 95 ameter to receive a coin of the denomination required to operate the machine and which when said slide is in its outermost position is positioned just without the wall A of the box, as shown more clearly in Fig. 5. A corre- 100 sponding aperture a³ is provided in the outer end of the table A³, which is concentric with 105

the aperture b^5 when the slide is in its outermost position and is slightly smaller and through which coins or other articles of smaller size than the operating-coin will fall if an attempt be made to operate the machine thereby. Said table is provided centrally with a semicircular aperture a^4 of a diameter transversely approximately equal to that of the aperture a^3 , but the dimension of which 5 longitudinally of the table is greater than the radius of said aperture and is adapted, in case a smaller coin or other article passes by the aperture a^3 , to allow said coin or article to drop therethrough and fall to the bottom 10 of the case without coming in contact with the operating mechanism. Intermediate said aperture a^4 and the inner end of the table is an aperture a^5 , similar to the aperture a^4 and of a transverse diameter equal to the 15 diameter of the aperture b^5 in the feed-slide. Said aperture is adapted to permit the operating-coin to fall therethrough when the feed-slide B is at the innermost limit of its movement and is provided with an adjustably- 20 weighted lid or cover a^6 , which fits loosely 25 and is pivoted by its outer edge in said aperture flush with the upper surface of the table. A laterally and forwardly directed arm a^7 is 30 rigidly engaged on the front edge of said cover and is journaled in the frame member A^2 , with the free end opposite from the lid or cover along the outer side of said frame member, as shown more clearly in Fig. 8, and is provided with an adjustable weight a^8 , 35 whereby said door or lid is counterbalanced to the weight of the required operating-coin, so that should a coin or other article of lighter weight pass the apertures a^3 and a^4 said cover will remain in its closed position and compel 40 said article to be returned upon the retraction of the feed-slide B.

Rigidly engaged on the inner face of the standard A' is a central guide C, extending longitudinally of the table intermediate the 45 inner ends of the stud-shafts and comprising, as shown, a metallic strip c and adapted to engage the upper surface of the feed-slide as it is projected inwardly and to hold the coin within the aperture b^5 . Said metallic strip c 50 is provided at its forward end with an upwardly-directed lug c' , affording means for securing the guide upon the frame member A' , and laterally with an upturned flange or web c^2 , which braces the guide and gives it 55 the desired rigidity. As shown, the strip c is offset centrally, thereby elevating the portion c^3 to a height above the aperture a^5 , and at the inner end thereof is rigidly engaged upon the flange a^2 on the inner end of said 60 table in any suitable manner. The end portion c^3 of the guide is provided with an upwardly-directed web c^5 above the aperture a^5 . A magnet c^6 is adjustably engaged upon the web c^5 by means of a clamping-plate c^7 and 65 screw c^8 or other suitable means and extends

downwardly with its poles adjusted a sufficient distance above the aperture a^5 in the table to permit the feed-slide B, with a coin therein, to pass beneath the same and close enough thereto to attract and hold an iron or 70 steel disk or other article which may have been inserted into the feed-slide and have failed to pass through either of the apertures a^3 or a^4 . Such blank or slug is thus retained in the aperture b^5 in the feed-slide, which 75 returns the same when the said feed-slide returns to its normal position.

Rigidly engaged on the under side of the table A^3 , beneath the aperture a^5 , by means of bolts or in any other desired manner, is the 80 coin-chute D, of metal or any other desired material, which is provided, as shown more clearly in Fig. 7, with a longitudinal slot near each side thereof, (indicated, respectively, by d and d'), and which extend upwardly there- 85 through to near top of the chute.

A lever E is pivoted, as shown, by means of a stud-bolt e, upon the outer end of a transverse shaft E' , which is rigidly engaged upon the lower inner corner of the frame member A^2 , though, obviously, said lever may be supported by any desired means to extend upwardly beyond the table A^3 in close relation with the edge thereof opposite the frame member A^2 . Said lever E is provided with a 90 forwardly-curved upper end e' , adapted to be engaged by the stud-shaft or trunnion b^3 , and which is normally held against said trunnion when the feed-slide B is in its outermost position by means of a spring e^2 , which is engaged 95 at one end on said lever and at the other is engaged upon the side of frame member A' , as shown in Figs. 2, 3, and 7. Said lever E is provided centrally with a laterally-directed arm e^3 , which extends behind the chute D 100 and has rigidly secured thereon a forwardly-directed finger e^4 in position to normally extend through the lower portion of the slot d in said chute, but which when said lever is forced rearwardly by the feed-slide B, as 105 shown more clearly in Fig. 4, is retracted from said slot and held above the upper end thereof.

Pivoted on the outer side of the frame member A^2 is a lever F, the upper arm f of which 110 projects above the table A^3 into position to be engaged by the stud-shaft or trunnion b^4 and the lower end of which extends downwardly and rearwardly and is provided with a hammer f' , adapted to contact with the 115 gong F^2 of any suitable construction, but herein shown as a coiled spring, one end of which is rigidly engaged upon the shaft E' on the outer side of the frame member A^2 . Said hammer f' , as shown, is normally held in 120 close relation with the gong F^2 or striking position by means of a spring f^3 , one end of which is rigidly engaged upon the frame member A' and the other of which is on the upper 125 arm f .

A shaft C is journaled forward of the lever F near the top of the frame member A² and in a downwardly-extending lug g on the under side of the table A³. Rigidly secured on said shaft at the side of the frame member A² is a rearwardly-curved detent G', provided on its upper surface with teeth g', adapted to engage a laterally-projecting lug f² on the lever F when the hammer is thrown forwardly by the inward movement of the feed-slide B. For the purpose of insuring positive engagement of the detent with said lever F a spring G², herein shown as a spiral pulling-spring, is engaged at one end to said detent and at the other end to the arm f of said lever and acts, upon the operation of the lever F, to force the detent G' rearwardly into position for the teeth g' to engage upon the lug f² and hold the hammer f' in its retracted position, as shown in Fig. 4. Adjustably engaged upon said shaft G on the inner side of the frame member A² by means of a set-screw h is a sleeve H, provided with a downwardly and laterally extending rod or trigger-arm h', which is normally held in front of said chute, as shown more plainly in Figs. 3 and 6, but which when said detent is actuated by the operation of the lever F is thrown rearwardly, by the rotation of the shaft G, into the slot d' in the chute D, as shown in Fig. 4, and is held in said position by engagement of the detent with the lug f².

If the device is to be used in connection with a pay-telephone system, the line-wire I of which is electrically connected to the frame member A' by means of the binding-pin i and to the curved contact-piece i', rigidly engaged upon the outer side of the frame member A², the latter is insulated therefrom by means of any desired insulating material i². Said contact-piece i' extends laterally into position to be engaged by the lever F when the lower end of the same is thrown forwardly by the action of the feed-slide B, and a signal is transmitted to the central operator by means of a signal-light i³, situated within the station of said operator. As a further signal the sound produced by the striking of the hammer f' on the gong F² upon its release is transmitted over the line-wire to the central operator, thereby giving a double signal.

The operation is as follows: The feed-slide is normally held in its extended position by means of the pressure exerted by the lever E upon the stud-shaft or trunnion b³, which is rigidly held in engagement therewith by the pull of the spring e². When said feed-slide is in its normal position, the aperture b⁵ is without the casing A and is in register and concentric with the aperture a³ in the table A³, so that a coin of the desired denomination may be placed therein and rest upon the said table below, though a smaller coin or slug would fall through. When said feed-slide is pro-

jected inwardly to its innermost position, as shown in Fig. 4, the aperture b⁵ is immediately above the aperture a⁵ through the inner end of the table, and the coin when it reaches this position, if of proper weight, trips the lid 70 or cover a⁶ and falls downwardly into the chute D. During the inward movement of the feed-slide B the lever E is thrown rearwardly by the trunnion b³ and the finger e⁴ is retracted from the slot d in the chute and 75 is held elevated above said slot, as shown in Fig. 4. The end of the lever F is also engaged by the trunnion b⁴, thereby throwing the lower end of said lever forwardly into engagement with the detent G', which by the 80 action of the spring G² is forced rearwardly and upwardly. The movement of said detent causes rotation of the shaft G, thereby throwing the trigger rod or arm h' into the slot d', as shown in Fig. 4, and into position 85 for contact with the coin as it falls into the chute. The pull of the spring e² returns the lever E to its normal position, thereby projecting the finger e⁴ back through the slot d of the chute, forcing the coin, together with 90 the trigger-finger h', downwardly, thereby releasing the detent G' from the lug f² on the lever F and causing the hammer f' by the action of the spring f³ to swing violently forward into contact with the gong F². The 95 sound caused by the striking of said gong is transmitted over the wire to the central operator or if used in any other class of vending-machines it affords an audible signal to the party purchasing that his coin has been 100 deposited in the proper place. When used in a telephone system, the lever F simultaneously engages with the contact-piece i', thereby completing the circuit and lighting the operator's signal-light i³. If a coin of 105 smaller size than the denomination required to operate the machine be inserted, it will fall through the aperture a³ in the table A³ and fail to enter the machine. Should, however, the party operating the machine hold 110 it within the aperture b⁵ of the feed-slide and project it into the interior of the casing, said coin or other article used will fall through the aperture a⁴ in the table and drop to the bottom of the casing without operating the signals above described. Should, however, a coin of different denomination or a disk or 115 other article succeed in passing the aperture a⁴, it will, if of lighter weight than the coin required to operate the machine, fail to trip the lid a⁶ and when the slide is returned to its normal position it will be returned therewith for removal. If a steel or iron disk of any weight succeeds in passing both the apertures a³ and a⁴ in said table, the magnet c⁶ engages and supports the same until retracted by the feed-slide to its normal position. Said magnet as herein shown is a permanent magnet, though, obviously, when the device is 120 used with an electrical circuit a temporary 125

magnet may be used and said magnet may be supported above the table A³ in any desired manner.

While the device has been shown as used in connection with a telephone system, it is obvious that it may be used with any class of vending-machine in which coins of a given denomination are used as an operating means.

10 I have described but one of several constructions embraced in my invention. I therefore do not desire to be limited otherwise than necessitated by the prior art, as obviously many details of construction may be varied without departing from the principle 15 of this invention.

I claim as my invention—

1. In a device of the class described the combination with a table having a plurality 20 of apertures therethrough, one of which is large enough to permit the passage of a given coin, means for depositing a coin in said aperture, a chute beneath said aperture, a lever actuated by said coin-depositing means, a 25 swinging arm adapted to close the passage through said chute, a detent rigidly connected therewith, a spring engaging said lever and detent and adapted when the lever is operated to engage the detent with the lever 30 and hold the arm in position to close the chute and means for ejecting the coin from the chute.

2. In a device of the class described the combination with a table having a plurality 35 of apertures therethrough, but one of which is large enough to receive a coin of a given denomination, of a normally open chute rigidly engaged beneath said larger aperture, means adapted to deposit a coin or the like in 40 said chute, a swinging arm operated thereby adapted to enter the chute and retard the coin and signaling means actuated by the coin-depositing means adapted to indicate the passage of said coin through the chute.

45 3. In a device of the class described, a table provided with a plurality of different-sized apertures therethrough, a feed-slide 50 movably engaged thereon and having an aperture adapted to register with one of the apertures in said table, a slotted chute rigidly engaged beneath one of the apertures of said table, means operated by the feed-slide adapted to enter the chute and retard the passage 55 of the articles therethrough, and means actuated by said feed-slide adapted to indicate the passage of an article through said chute.

60 4. In a device of the class described, the combination with a rigid frame of a table rigidly engaged thereon and provided with a 65 plurality of apertures, an apertured feed-slide movable longitudinally of said table, a slotted chute leading from one of the apertures in said table, means operated by the feed-slide and acting through said slots to control 70 the passage through said chute, a hammer

operated by the inward movement of said slide and means for locking said hammer in one position and acting to release the same when a coin passes through the chute.

5. In an automatic signaling and detecting device the combination with a rigid frame of a table rigidly engaged thereon and provided with a plurality of different-sized apertures therethrough, a chute having a coin-receiving aperture therein adapted to 75 pass successively over the apertures in said table, a slotted chute rigidly engaged beneath the last aperture in said table, a swinging arm, a lever pivoted on the frame, a detent adapted to engage therewith and lock said arm to control the passage through the chute, means operating through a deposited coin for throwing said arm out of its controlling position, a hammer on said lever and means adjacent thereto adapted to afford an audible signal when the feed-slide is retracted. 85

6. In a device of the class described the combination with a rigid frame of a table rigidly engaged thereon provided with a plurality of apertures, means adapted normally 90 to close one of said apertures, a slotted chute leading from said closed aperture, a feed-slide movably engaged on said table adapted to deposit a coin in said chute, a swinging arm, means for locking said arm in position 95 to arrest the passage of said coin through said chute, means adapted to engage the coin and release said arm, a gong, and a hammer carried on said locking means and adapted when said arm is released to strike said gong. 100

7. In a device of the class described the combination with a table having a plurality of apertures therethrough of a slotted chute rigidly engaged beneath one of said apertures, a feed-slide movably engaged on said 105 table, a spring-controlled lever adapted to normally hold said slide in its extended position, a hammer pivoted in position to engage said slide, a depending arm, a detent operatively connected therewith adapted to engage said hammer and lock said arm in position to obstruct the passage in said chute and means on said lever adapted to force an article through the chute and release said arm. 110

8. In a device of the class described the 115 combination with an apertured table provided with a slotted chute on the under side thereof, of a feed-slide adapted to carry a coin or the like and deposit it in said chute, a spring-controlled hammer adapted to be engaged by said feed-slide, a detent adapted to engage said hammer, an arm adapted to be locked by said detent in the slot of said chute and means adapted to strike said coin and release the hammer. 120

9. In a device of the class described the combination with an apertured table provided with a chute beneath the same, a slide movably engaged thereon adapted to feed a coin through said chute, a gong, a spring- 125 130

controlled hammer pivoted on said table and projecting upwardly in position to be engaged by said slide, a transverse shaft, a detent thereon adapted to engage said hammer and hold it retracted, an adjustable arm on said shaft adapted when the detent is engaged with said hammer to obstruct the passage through said chute, a spring-controlled lever adapted to be actuated by said slide and a finger thereon adapted when said lever is released, to engage said coin and release said detent and force said hammer against said gong.

10. In an automatic signaling and detecting device an apertured table, a slotted feed-chute beneath the aperture of said table, a shaft journaled beneath the table, an arm thereon, a rearwardly-curved detent on the end of said shaft, a lever pivoted on the side 15 of the table adjacent the detent, a spring connecting said detent and lever, a feed-slide adapted to swing said arm into the slot in said chute and engage the detent with the lever, a lever on the opposite side of the table 20 also operated by the feed-slide and an arm thereon operating through a deposited coin to disengage the detent from the aforesaid lever.

11. In an automatic signaling and detecting device an apertured table, a feed-slide thereon adapted to deposit the operating-disk, a lever pivoted at each side of the table and one of which is provided with a hammer, laterally-directed trunnions on said slide 25 adapted to engage and operate said levers, a normally open chute beneath the table, a swinging arm adjacent said chute, means connected therewith acting when one of said levers is operated to lock the arm across the 30 chute to retard the progress of said disk, a gong and means on the other lever adapted to enter the chute and through a deposited

coin to release the disk and throw the hammer against said gong.

12. In a device of the class described an 45 apertured table, an apertured slideable feed-slide thereon, a normally opened chute beneath the aperture in said table, means adapted to close the chute when the feed-slide is operated, a lever pivoted at the side 50 of the table, a laterally-directed trunnion on said slide adapted to be engaged by said lever, a spring engaged on said lever and acting to hold the slide extended, a rod rigidly engaged on said lever and adapted to force an 55 article through the chute, and means connected with and operated from the means for closing the chute adapted to produce an audible signal when the article passes through the chute.

13. In a device of the class described the combination with a table having a plurality of apertures therethrough, of a pivotally-supported lid adapted to close one of said apertures, a coin-carrying slide movably engaged on said table, means acting to normally hold said slide extended from the table, a guide rigidly engaged on the table in close relation to said slide, a normally opened chute below said aperture, an arm pivoted 60 adjacent the chute, a lever adapted to swing said arm across the chute, means for locking the arm in the chute, means for releasing said arm and means operated by said slide for indicating the passage of a coin through the 65 chute.

In testimony whereof I have hereunto subscribed my name in the presence of two subscribing witnesses.

EDWIN L. HARMAN.
